UNITED STATES PATENT OFFICE.

FREDERICK BOY MOELLER, OF PHILADELPHIA, PENNSYLVANIA.

CALENDAR.

SPECIFICATION forming part of Letters Patent No. 662,954, dated December 4, 1900.

Application filed September 29, 1900. Serial No. 31,522. (No model.)

To all whom it may concern:

Be it known that I, FREDERICK BOY MOELLER, a citizen of the United States, residing at Philadelphia, in the county of Philadelphia and State of Pennsylvania, have invented a new and useful Calendar, of which the following is a specification.

This invention relates to calendars in general, and more particularly to the class of perpetual calendars, one object of the invention being to provide a construction wherein the days of any month of any year from 1752 may be correctly shown, the number of years being limited only by the dimensions.

15 A further object of the invention is to provide a construction wherein the numbers of the leap-years are separately grouped and wherein the month-names of "January" and "February" will be automatically shifted to 20 correspond to the leap-years, it being understood that in the leap-years January has the same calendar as July, while in other years it has the same calendar as October, this arrangement eliminating the necessity for mental calculation for leap-years.

25 Further objects and advantages of the invention will be evident from the following description.

In the drawings forming a portion of this 30 specification and in which like numerals of reference indicate similar parts in the several views, Figure 1 is a top plan view showing the complete calendar set to show the month of September, 1900. Fig. 2 is a vertical diametrical section of Fig. 1. Fig. 3 is a plan view of the intermediate disk of the calendar. Fig. 4 is a plan view showing the bottom disk of the calendar.

Referring now to the drawings, the calendar 35 comprises three disks *a*, *b*, and *c*, of which the lower disk is provided with a number of curved rows *d* of numbers which represent the days of weeks, these curved rows being arranged spirally, with their inner ends 40 resting upon the periphery of a common circle *e*. The numbers are also separated by division-lines *f* into a plurality of columns which lie radially of the disk. The numbers in each spiral row begin with "1," and the 45 numbers in four successive rows run to "31," inclusive; the next five rows run to "30," inclusive; the next two rows run to "29,"

inclusive, and the last two rows run to "28," inclusive. There are thus thirteen spiral rows, and the inner ends thereof are spaced 55 six columns apart, as shown in Fig. 4 of the drawings, whereby by beginning with "1" in any row it is possible to count to "7," then drop to the number under "1" and count to "14," then drop to the next number under 60 "1" and count to "21," and continue this dropping until the last end of a spiral row is reached. In other words, it is possible to divide the entire group of numbers into a series of segmental groups wherein portions of 65 the several rows of numbers will be utilized to present a succession of numbers running from "1" to "28," "29," "30," or "31," as the case may be. The number of segmental groups possible is limited by the number of 70 columns of numbers, which is ninety-one.

To present each single segmental group by itself, the disk *c* is provided and has a segmental opening *g* therein, which opening is of sufficient width to uncover seven columns 75 of numbers. At the minor end of the segmental opening are marked the initials of the days of the week, beginning with Sunday. The ninety-one possible segmental groups of 80 numbers correspond to the days of the months throughout the limits of the calendar above expressed; but some means must of course be provided for showing the proper group when a certain definite month is to be represented. For this purpose the intermediate 85 disk *b* is provided and has printed upon its upper face adjacent its edge which projects from under the edge of the disk *c* the names of the months of "November," "June," "September," and "April" in one group, 90 the months of "December," "July," "October," "May," "August," and "March" in a second group, and "February" standing alone. The disk *a* has a pointer *h*, which is adapted for alinement with the month-names 95 successively. January has the same calendar as October in common years and the same as July in leap-years, and for this reason January is represented twice, once in each of its two positions, but spaced differently from the edge of the disk *b*, so that one may be covered and the other uncovered at proper times. To effect this covering and uncovering, disk *c* has a segmental recess *i* 100

in its edge to uncover the "January" name opposite to "October," and directly adjacent thereto is a segmental opening *j*, positioned to uncover the second "January" name when the first "January" name is covered. There is also a second "February" name, which is normally covered by the disk *c* and at which time the first "February" name is exposed through the recess *k* in the edge of disk *c*, and when disk *c* is moved to cover the first "February" name it uncovers the second "February" name. The covering and uncovering of the "January" and "February" names are effected by shifting disk *c* with respect to disk *b* to set the calendar for the years.

To provide for setting the calendar at the proper years, two groups of numbers *l* and *m* are represented upon the disk *c*, each number of one group representing the last two figures of the date of each common year, while each number of the second group represents the last two figures of each leap-year date. Upon the protruding edge of disk *b* are marked "17," "18," and "19," representing the three centuries for which the calendar is used.

The operation of the calendar is as follows: Supposing that the month of September, 1900, is to be shown, then the disk *b* is rotated to bring the number "19" upon its edge in line with the two naughts "00" on disk *c*. This will give the opening *g* the proper position with respect to the year-date, and the disk *a* is then rotated to bring the pointer *h* opposite to the month-name "September," which action will bring the proper group of numbers on disk *a* beneath the segmental opening *g* for exposure therethrough, as shown in Fig. 1 of the drawings. It will be noted that when the disk *a* is moved to bring the century-numbers—*i. e.*, "17," "18," and "19"—opposite the common-year group of figures *l* the outer "February" name is exposed and the "January" name opposite to "October" is exposed. When the disk *b* is moved to bring the century-numbers opposite to the leap-year group *m*, then the inner "February" name is exposed and the outer one is covered, and at the same time the outer "January" name is covered and the "January" name opposite to "July" is exposed. Thus in adjusting the calendar for February or January of a leap-year the group of numbers exposed through the opening *g* is entirely different from the group exposed when the calendar is adjusted for a common year. It will thus be seen that for any month of any year within the limits of the calendar there is no calculation necessary, but instead the disks are shifted to give the proper exposure through the opening *g* at all times, while the calendar will also show the month-name and the year-date to which the exposed day-numbers relate.

It will be understood that in practice any suitable materials and proportions may be used and that various modifications of the specific construction shown may be made without departing from the spirit of the invention, it being also understood that the several disks are pivotally connected in axial alinement. Also it will be noted that the disk *b* has an opening *n* for registration with the opening *g* to permit exposure of the month-numbers or day-numbers of the months.

What is claimed is—

1. A calendar comprising a plate having represented thereon a group of the last figures of the common-year dates of a century and a separate group of the last figures of the leap-year dates of a century, a second plate having the first figures of several centuries marked thereon and adapted for alinement with the figures of the groups of the first plate interchangeably, the second plate having also month-names thereon, and a third plate below the second plate and having a plurality of columns of figures thereon and having a pointer for alinement with the month-names interchangeably, the several plates being pivotally connected for adjustment with respect to each other, and the first two plates having openings for alinement to expose groups of figures of the third plate.

2. A calendar comprising a plate having represented thereon a group of the last figures of the common-year names of a century and a separate group of the last figures of the leap-year dates of a century, a second plate having the first figures of several centuries marked thereon and adapted for alinement with the figures of the groups of the first plate interchangeably, the second plate having also month-names thereon, the names of certain months being repeated in different positions, and a third plate below the second plate and having a plurality of columns of figures thereon and having a pointer for alinement with the month-names interchangeably, the first plate being formed to expose different of the repeated month-names as the century first figures are shifted from one to the other of the groups of last century figures, the several plates being pivotally connected and the first and second plates having openings therein for alinement to expose groups of figures on the third plate to correspond to the century and year indicated by the first and second plates.

In testimony that I claim the foregoing as my own I have hereto affixed my signature in the presence of two witnesses.

FREDERICK BOY MOELLER.
